(57) CLAIM

The ornamental design for shirt pen pocket, as shown and described.

DESCRIPTION

FIG. 1 is a perspective view of shirt pen pocket showing my new design, with a pen shown in broken lines to show use; FIG. 2 is an enlarged perspective view of the shirt pen pocket; FIG. 3 is a front side elevational view thereof; FIG. 4 is a left side elevational view thereof; and, FIG. 5 is a right side elevational view thereof. The broken lines shown represent unclaimed subject matter and form no part of the claimed design.
